UNITED STATES PATENT OFFICE.

WILLIS E. ROYS, OF RICHMOND HILL, NEW YORK.

MAGAZINE-FEED BOILER.

1,244,375.

Specification of Letters Patent. Patented Oct. 23, 1917.

Application filed February 15, 1916. Serial No. 78,428.

To all whom it may concern:

Be it known that I, WILLIS E. Roys, a citizen of the United States of America, residing at Richmond Hill, Long Island, New York, have invented a new and useful Magazine-Feed Boiler, of which the following is a specification.

The general objects of my present invention are to provide simple and effective 10 means for automatically feeding fuel to a boiler furnace.

A special object of the invention is to obtain a substantially uniform feed of fuel over the grate surface, and to maintain a 15 substantially even depth of fuel bed.

Another object of the invention is to provide a fuel feeding device of the character set forth, capable of ready application to furnaces in use at the present time.

20 In the accomplishment of these and other objects, I employ a fuel distributing head which is mounted in the combustion chamber of the furnace above the grate and is provided with distributing troughs extending 25 to different points over the grate so as to distribute the fuel more or less uniformly over the grate area. The fuel is fed to this distributing head preferably through a downwardly inclined chute extending from 30 a suitable supply hopper. To prevent ignition of the fuel in the feed chute and distributing troughs, before it actually reaches the fuel bed, I provide the distributing head and troughs with a water jacket. This prevents 35 premature ignition of the fuel, protects the distribution head from burning out and also provides additional heating surface for the boiler.

Other features and details of construction 40 will become apparent as the specification proceeds, attention being directed to the accompanying drawing, wherein is illustrated a practical and preferred form the invention may take.

45 In this drawing:

Figure 1 is a perspective view showing my invention applied to a boiler of the so-called "sectional" type, the front section of the boiler being omitted so as to show the distributor head in place within the combustion chamber.

Fig. 2 is a part sectional view taken partly on the plane of the line 2-2 of Fig. 1 to illustrate the manner of applying the apparatus to this type of boiler.

Fig. 3 is a sectional view taken substantially on the plane of the line 3-3 of Fig. 2.

Fig. 4 is a cross sectional view of the distributor head taken substantially on the plane of the line 4-4, Fig. 2.

The boiler illustrated is made up of hollow vertical sections 7 arranged in abutting relation and suitably connected to provide the proper circulation through the different sections. In the particular construction 65 illustrated these sections are arched to provide a combustion space or fire pot 8 above the grate 9.

The fuel is supplied from a hopper 11 located, in this instance, outside the furnace 70 and supported on the upper end of the inclined feed chute 12 which extends on an incline downward into the combustion chamber. This hopper may be braced at the top by rods 13 connecting with the hopper 75 and engaged in upstanding members 14 which may be formed as lugs on certain of the furnace sections. The lower side walls and the outer end walls of the hopper are preferably converged downwardly to the 80 mouth of the feed chute as indicated at 15 to produce proper feeding of the coal or other fuel. The hopper is further provided with a door 16 at the top thereof which may be hinged as indicated at 17 and this charging door is made relatively close fitting so as to prevent the escape of gases.

A passage for the entry of the feed chute 12 down into the combustion chamber is provided in the furnace illustrated by making two of the abutting sections with complementary recesses 20 in their abutting faces which as indicated in Fig. 3 form, when the sections are assembled, a passage extending downward on an incline into the 95 upper portion of the combustion chamber. The feed chute may be supported in this downwardly inclined passage by providing it with a lug 21 on its under side near the top thereof arranged to bear against the 100 outer surface of the recessed sections and form a stop limiting the downward movement of the chute in said passage. By such means the feed chute is positioned by the mere insertion of the chute in the passage 105 designed to receive it and the hopper may be secured to the chute by providing it with dependent lugs 22 through which fastenings 23 are passed into the top of the chute. At

the lower end of the feed chute, inside the 110

combustion chamber, a distributer is placed. This distributer comprises a head 25 in communication with the lower end of the feed chute and provided with a plurality of distributing troughs 26. In the construction illustrated there are four such distributing troughs arranged in diverging relation with two extending toward each end of the furnace.

- 10 The distributing troughs, like the feed chute are also arranged on a downward incline and this incline is such that the fuel will flow easily but will come to rest as soon as the flow at the mouths of the troughs is checked, or in other words, as soon as the fuel pile on the grate reaches the mouths of the troughs. A fuel bed of any desired depth can therefore be maintained by locating the distributer in the combustion chamber 15 at a point where the flow from the troughs will be checked by the discharge piles when these piles have reached the height desired to be maintained on the grate. By locating the distributer with the mouths 20 of the troughs at a higher level a greater depth of fuel bed will be maintained and conversely by lowering the distributer a fuel bed of less depth will be maintained. By increasing the number of distributing 25 troughs a more even distribution of the fuel over the grate can be secured.

To prevent burning the distributer and to prevent premature ignition of the fuel in the feed chute or distributing troughs the distributer, including the head portion and the diverging troughs are preferably formed with a double bottom providing a water jacket 30, and use is made of this water jacket as additional heating surface by coupling it up with the heater sections through piping 31 entered into the opposite sides of the distributer head. This piping is utilized also, in this case, as the means for supporting the distributer within the combustion 35 chamber.

From the foregoing it will be understood that as the coal on the grate is consumed and the level of the fire bed is thereby lowered additional fuel will flow down the feed chute

and distributing troughs until the fire bed 50 is again brought up to the desired predetermined level. It will also be clear that in case the fuel burns more rapidly at one point on the grate than at another point more fuel will automatically be distributed where the 55 greater consumption takes place. The invention is simple and relatively inexpensive and has proved to be practical for the purposes intended.

What I claim is:—

1. In combination with a furnace having hollow walls forming a combustion chamber, a fuel distributer located in said combustion chamber, said fuel distributer having a water jacket in the bottom thereof and piping extending from the water jacket of said distributer to the hollow walls of the furnace and thereby supporting said distributer within the combustion chamber.

2. In combination with a furnace having 70 a combustion chamber and a passage extending in through the side of the furnace on a downward incline into the combustion chamber, a downwardly inclined stationary feed chute located in said passage and supported by the walls of the passage, said feed chute having a lug on its outer upper end portion engaging with the furnace and limiting the extent of downward movement of the feed chute in the movement passage, a feed hopper on the outer upper end of the feed chute and a fuel distributer in the combustion chamber in communication with the lower inner end of the feed chute.

3. In a device of the character set forth a 85 furnace having a combustion chamber and a grate, a fuel distributer in said combustion chamber having distributing troughs inclined downwardly on an angle such that the fuel therein will come to rest when checked 90 by the pile of fuel discharged therefrom and resting on the grate, said distributer being mounted with the mouths of the distributing troughs at substantially the height of the fuel bed desired to be maintained on the 95 grate and means for supplying fuel to said distributer.

WILLIS E. ROYS.
